[57] CLAIM

The ornamental design for an integrated-circuit package removal tool, as shown and described.

DESCRIPTION

FIG. 1 is a perspective view of an integrated-circuit package removal tool showing my design;

FIG. 2 is a side elevational view; the opposite side being a mirror image thereof;

FIG. 3 is a front elevational view;

FIG. 4 is a rear elevational view;

FIG. 5 is a top plan view; and

FIG. 6 is a bottom plan view thereof.
